UNITED STATES PATENT OFFICE.

THOMAS W. BURR, OF STONEHAM, MASSACHUSETTS.

CARBURETER.

1,325,689.

Specification of Letters Patent. Patented Dec. 23, 1919.

Application filed November 28, 1917. Serial No. 204,448.

To all whom it may concern:

Be it known that I, THOMAS W. BURR, a citizen of the United States, and a resident of Stoneham, county of Middlesex, and 5 State of Massachusetts, have invented an Improvement in Carbureters, of which the following is a specification.

This invention relates to certain improvements in carbureters of the type in which the liquid fuel is drawn up thereto from a low level tank, which is open to atmospheric pressure, by the suction action of the engine; and more particularly to certain improvements in a fuel feeding device of the type 15 disclosed in my pending application, Serial No. 196,943, in which no auxiliary reservoir is employed, the supply pipe leading directly from the main tank to the carbureting chamber, so that it is practically "dry" at all 20 times in that it, at no time, contains any substantial quantity of fuel in liquid form.

In this device also, the liquid fuel supply pipe, which extends from the low-level tank, opens to the carbureting chamber at the engine side of the throttle, which controls the air supply thereto, so that said pipe is open 25 to the full suction action of the engine, and the discharge therefrom is controlled by a needle valve which is automatically operated 30 with the throttle in predetermined proportion, so that the relative proportions of air and fuel are essentially maintained under all conditions.

The object of the present invention is primarily to provide a simplified form of device having the above characteristics, so that the cost of manufacture thereof may be reduced, as compared with prior devices for the purpose; and the danger of its getting out of 35 order will be reduced to a minimum, and to accomplish this object without impairment of efficiency, but with possible increase in efficiency.

I accomplish this object by means herein- 40 after described and illustrated in the accompanying drawing, in which:

Figure 1 is a side elevation of fuel feeding device embodying my invention.

Fig. 2 is a plan view thereof.

Fig. 3 is a sectional view on the line 3—3 of Fig. 2.

Fig. 4 is a sectional view on the line 4—4 of Fig. 1.

Fig. 5 is a general view, illustrating the combination.

As shown in the drawing, the liquid vaporizing device, embodying the present invention, comprises a casing *a* of cylindrical form, having ears *a'* at one end, adapted to connect the same directly to the intake manifold of the engine, and having its opposite end closed by a cap *b* removably secured thereto. An air supply pipe *c*, of substantially smaller internal cross-sectional area than that of said casing, and which, in practice, is arranged so that the air passing therethrough will be heated, is connected to said casing at right angles; and a hollow cylindrical throttle valve *d*, closed at one end and open at the opposite end, and having a port *d'* in one side thereof, is disposed in said casing with its closed end adjacent said cap *b*, and so arranged that, when rotated, its port may be brought into register with the opening in the casing to which the air supply pipe *c* is connected. The head end of said valve *d* is provided with a tubular stem *e* which extends through said cap *b* and is rotatable therein, and a nut *f*, having an operating arm *f'* extending therefrom, is 75 mounted on the outer end of said stem and is locked in position thereon by a set screw *g*, or other suitable means, to provide means for controlling said valve, the movements of which are limited by fingers *h* on said 80 arm, arranged to engage a stop lug *i* on the cap *b*.

The liquid fuel supply pipe *j* is extended from the bottom of a suitably vented, low level, liquid fuel supply tank *k* into said 90 casing, at a point between the open end of the throttle valve and the end of the casing which is connected directly to the intake manifold; the inner end of said pipe being extended beyond the longitudinal center of 95 said casing, and having a nipple *m* mounted therein, the center line of its bore being coincident with the center line of the casing, having a side opening connecting said bore with said supply pipe *j*. The bore of said 100 nipple, next the suction end of the casing, is preferably enlarged and covered with a

fine mesh screen m' , as shown in Fig. 4, and a shoulder m^2 is formed in said bore between said enlargement and the point of connection of said supply pipe therewith. A tapering valve seat is formed in said shoulder; against which a needle valve n is adapted to seat, the stem of which is extended through and threaded in the stem e of the throttle valve and through the bore of said nipple. 10 The outer end of the needle valve stem is provided with a head o , by means of which it may be conveniently adjusted, and a lock nut p is provided on said stem for locking the same in adjusted position. An inclined 15 cam-faced projection b' is formed on the outer end of the head concentrically with the needle valve stem, and a correspondingly inclined cam face is formed on the nut j , said faces being constantly held in contact by a spring q surrounding the stem e and interposed between the inner side of the cap b and the head end of the valve d .

In practice the parts are so adjusted that when they are in initial position, and one 25 of the stop fingers h is in engagement with the lug i , both the throttle valve and the needle valve will be slightly open, so that when the engine is turned over and a partial vacuum is created within the casing, 30 the atmospheric pressure, on the surface of the liquid in the tank k , will force a small quantity of the liquid into the chamber, and, at the same time, a corresponding quantity of air, sufficient to make the explosive 35 mixture, will pass through the throttle valve port and become mixed therewith. Under these conditions only sufficient mixture will be supplied to run the engine without load. It will be understood that the exact initial 40 adjustments of the valves will depend to a large extent on conditions, and that the relative extent of opening of the two valves, when in initial position, will be varied according to particular requirements.

45 In the initial position of the throttle valve, its closed end is held at a sufficient distance from the cap b , to permit the same to be axially moved toward said cap for a distance equal to that which it is necessary to 50 move the needle-valve axially; to move the same from a position, in which it is seated, to its fully open position, so that when the arm f' is moved to open the throttle valve, as its cam nut f rides up on the cam projection b' , the throttle valve will be moved axially toward said cap as it is rotated, and as the needle valve n is mounted in the stem of the throttle valve, it will be carried away from its seat by the throttle valve, as 55 the latter is opened; the relative arrangements of cams and valve ports being such that the volume of air, which may be drawn in through the port d' of the throttle, and the volume of liquid which will be permitted

to escape past the needle valve, will be in 65 direct and constant proportion in all positions thereof. When the valves are closed, the opposite movements will take place, as will be obvious.

It is essential to the successful operation 70 of the above described device that the cross sectional area of the air inlet be less than that of the air suction chamber to which the engine is connected, so that the engine may act to reduce the air pressure in said chamber to a sufficient extent in the completely 75 open position of the throttle valve, to insure the discharge of liquid fuel into the mixing chamber in sufficient quantities to maintain the desired proportions of air and fuel. 80

The device above described is not only of simple construction, but it is unlikely to get out of order, and it is adapted to be adjusted to meet widely differing demands.

I claim:—

1. A carbureter comprising a casing having a carbureting chamber to which air and fuel are supplied, a cylindrical throttle valve mounted for axial movement in said casing and rotatable to vary the air supply to said chamber, a needle valve carried by said throttle valve in axial alinement therewith and arranged to be operated to vary the fuel supply to said chamber when moved axially, and means to cause simultaneous 90 axial and rotational movements of said throttle valve, to operate said needle valve, and to cause simultaneous and corresponding control of the air and fuel supply to said chamber. 100

2. A carbureter comprising a casing having a carbureting chamber to which air and fuel are supplied, a cylindrical throttle valve mounted for axial movement in said casing and rotatable to vary the air supply 105 to said chamber, a needle valve carried by said throttle valve in axial alinement therewith and arranged to be operated to vary the fuel supply to said chamber when moved axially, means to cause simultaneous axial and rotational movements of said throttle valve to operate said needle valve and simultaneously and correspondingly control the air and fuel supply to said chamber and means permitting axial adjustment of said 115 needle valve, while said throttle valve is held against rotation, to vary the fuel supply relative to the air supply.

3. A carbureter comprising a casing having a carbureting chamber to which air and fuel are supplied, a cylindrical throttle valve mounted for axial movement in said casing and rotatable to vary the air supply to said chamber, a needle valve carried by said throttle valve in axial alinement therewith and arranged to be operated to vary the fuel supply to said chamber when moved axially, means to move said throttle valve 120

rotationally to vary the air supply to said chamber, a spring arranged to move said throttle valve axially in one direction and a cam for moving it in the opposite direction when the valve is rotated, to cause corresponding axial movements of said needle valve and simultaneous and corresponding

control of the air and fuel supply to said chamber.

In testimony whereof, I have signed my name to this specification.

THOMAS W. BURR.
